2,601,462

METHOD FOR ATTACHING CONNECTIONS
TO STRANDED CABLES

William James Streader, Portslade, England, assignor to Tate Bros., Portslade, England, a British firm composed of William James Streader and Albert Edward Tate

Application February 27, 1946, Serial No. 650,560
In Great Britain November 3, 1944

1 Claim. (Cl. 29—148)

1

This application corresponds to the application of William James Streader, Alfred Tate, and Albert Edward Tate, Serial No. 21611/44, which was filed in Great Britain on November 3, 1944.

This invention is for an improved method and apparatus for attaching a connection to a stranded cable which connection is of the kind comprising a sleeve formed of metal, which is sufficiently ductile to enable it to be contracted on to the cable by distorting the metal of the sleeve. Heretofore, the sleeve was oval in cross-section and its distortion was effected by pressure applied across the major axis of the oval through a contractible multipart cylindrical die which at the end of the compression was arranged to contact with substantially the whole of the outer surface of the sleeve. It was only practical to operate upon a comparatively short length of the sleeve at a time, so the complete compression had to be carried out in a number of successive steps. This method of contracting the sleeve resulted in the sleeve being substantially elongated, which may be a serious objection, particularly when the connection is attached to an electric power cable comprising a stranded aluminum sheath surrounding a steel core. In such an instance, the elongation of the sleeve during distortion causes the aluminum strands to be pushed along the core and to bulge outwardly. An object of the present invention is to minimise or prevent elongation of the sleeve.

According to this invention, a method of attaching a sleeve of ductile metal to a stranded cable consists in subjecting the sleeve to radial pressure over a limited extent of its circumference. The extent of radial distortion of the sleeve may be so limited that the amount of metal pressed inwardly from the inner surface of the sleeve is not substantially greater than will fill the gaps between the strands of the cable opposite the distortion. It is found that if the amount of metal pressed inwardly is substantially greater than will fill the gaps, elongation of the sleeve at once takes place. Preferably, the radial pressure is so applied to said sleeve along a central stretch thereof terminating short of its ends.

Different portions of the circumference of the sleeve may be subjected to radial pressure in successive operations, so as to ensure that all the gaps between the strands are filled with the distorted metal, whereby a firm attachment is effected.

The sleeve may be subjected simultaneously to pressure at opposite ends of a diameter.

2

The sleeve may be indented in wavy formation by said pressure on each side thereof and along the greater part of the length thereof, so that the crests of the waves at one side of the sleeve lie opposite the troughs on the opposite side, thereby still further increasing the grip between the sleeve and the cable.

In one method of carrying the invention into effect, the stranded cable is encircled by said sleeve, and the sleeve is enclosed in a die and keys, or the like, are forced into the sleeve through slots in the die. Alternatively, the two parts of the die may be provided with fixed projections on the inner face thereof, and the two die parts are forced together on opposite sides of the sleeve. Preferably, the sleeve is enclosed in a die having a cylindrical surface of equal or slightly smaller diameter than that of the sleeve.

Thus, a two-part die for carrying out the method referred to above may comprise two parts, each of which comprises a semi-cylindrical depression having an axially-extending slot therein, a key in said slot, and means for limiting the travel of said key through said slot so that the amount of metal pressed inwardly from the sleeve is not substantially greater than will fill the gap between the strands opposite said key. The means for limiting the extent of movement of each key may comprise a head, or the like, on said key disposed outside said mould, and spring means may be provided for moving the keys outwardly from the cylindrical depression. Alternatively, each of said die parts may comprise a semi-cylindrical depression, and a fixed projection extending along the length of the depression, stopping short of each end. In this case, the extent of the projection is such that the amount of metal pressed inwardly from the sleeve is not substantially greater than will fill the gap between the strands opposite said key when the two parts of the die are forced together. In either of the arrangements referred to above, the cylindrical depression is arranged to have a length sufficient to cover a predetermined length of sleeve, while the keys or projections are of such a length as to contact along the central stretch of the sleeve leaving short end portions of the sleeve unaffected.

The following is a description of two different forms of connection for an aluminium sheath steel core cable and the means for effecting that connection, reference being made to the accompanying drawings, in which:

Figure 1 is a side elevation of one form of con-

nection before the parts thereof have been brought into register;

Figure 2 is a side elevation of another form of connection, also before the parts have been brought into register;

Figure 3 is an end elevation of a two-part die suitable for securing parts of the connection to the cable;

Figure 4 is a side elevation of the arrangement shown in Figure 3;

Figure 5 is an end elevation of an alternative form of two-part mould;

Figure 6 is a longitudinal section through a further alternative form of two-part mould, the keys being shown in side elevation, and

Figure 7 is an end elevation of one of the key members.

For electric power cables it is known to attach separate sleeves forming parts of a connection to the steel core and aluminium sheath, respectively, so that by anchoring the two parts of the connection together the tensile loads carried by the cable as a whole may be distributed between the core and the sheath. In the arrangement shown in Figure 1, one part of the connection 10 for attachment to the steel core 11 is formed from comparatively ductile mild steel and is provided with a forked portion 12 and a sleeve portion 13. The other part of the connection 14 is formed from aluminium or aluminium alloy, and is also provided with a forked portion 15, the width between the limbs of which is sufficient to enable it to be brought into register with the forked portion 12. It is also provided with a sleeve portion 16. The method of assembling the parts is as follows: The aluminium stranded sheath 17 is stripped away from the stranded steel core 11, and the aluminium connection part 14 is threaded over the aluminium sheath into the position shown in Figure 1. The steel part 10 of the connection is applied to the steel core so that the sheath 13 encircles it. A two-part die indicated generally at 18 is then placed over the steel sleeve which is indented by means of keys associated with the die parts, as hereinafter described, in one or a number of operations. The aluminium connection part 14 is then slid over the steel sleeve until the forked portions 12 and 15 are in register. In this position, the sleeve portion 16 of the part 14 still encircles the aluminium sheath, and this sleeve portion is indented by a two-part die similar to that referred to above. Since the method of contracting the aluminium sleeve on to the sheath does not result in elongation of the sleeve the two fork parts remain in register.

Figure 2 illustrates a method of joining together the ends of an aluminium sheath steel core cable. The aluminium sheath 17 is first stripped from both ends of the cable to expose the steel core 11. A steel sleeve 19 is then arranged to encircle the two steel core portions 11 and is of approximately the same diameter as that of the aluminium sheath 17. The steel sleeve 19 is then contracted on the core by means of a two-part die, indicated at 18. The aluminium sleeve 20 which was previously slid over one of the sheaths is now drawn over the steel sleeve 19 and is of sufficient length as still to overlap both sheath portions 17. The aluminium sleeve is then contracted on to the two sheath portions 17 by means of a two-part die, either in a single operation, or first one end is contracted on to the sheath, and then the other.

One form of two-part die 22 is shown in Figures

3 and 4. Each die part 22 is provided with a semi-cylindrical internal surface 21 of the same diameter as the aluminium sleeve or steel sleeve, according to which part it is to operate upon. The length of each die part 22 is greater than the length of the sleeve portion with which it is to be used, and is provided with a slot through which extends a key 23 of a length preferably shorter than the length of the sleeve to be contracted. Each key may be provided with a wavy edge having crests and troughs 24 and 25 so that the crests on one key are arranged opposite the troughs in the other. The radial width of the keys is such that they may project into the cylindrical inner surface of the die to a predetermined extent which is determined by a head 28 formed at the outer end of each key. The faces of the keys exposed to the sheath may be part-cylindrical. The keys may be forced outwardly away from the inner faces of the die by compression springs 26 accommodated in sockets in the aforesaid head 28 and in the die-part.

In the arrangement shown in Figure 5, instead of the die-part 22 being slotted to receive a sliding key, each is provided with a projection 27 extending along the length thereof, which is of a similar width, and projects to a similar extent to the key shown in Figures 3 and 4, when that key has been forced to its limit.

In effecting the attachment of the sleeve of aluminium alloy to a cable having a steel core made up of seven strands and having an overall diameter of about $1\frac{1}{2}$ inches and a sheath of twelve aluminium strands making up an overall diameter of about $\frac{3}{4}$ of an inch, the surrounding sleeve has an external diameter of about $1\frac{1}{2}$ inches and an internal diameter of such size as to provide an easy sliding fit with the core. The width of the key on a die-part is about $\frac{1}{2}$ an inch, and in the case where the key is fixed in the die-part its radial height is about $\frac{3}{4}$ of an inch. Under these conditions, the sleeve requires to be subjected to radial pressure only at four equally disposed locations around its circumference. The sleeve thus requires to be subjected to two pressing operations in a two-part die as referred to above. The internal surfaces of the die are preferably cylindrical and have a diameter slightly larger than $1\frac{1}{2}$ inches. Alternatively, as indicated above, the keys may be mounted to slide radially in slots formed in the die parts and are so arranged that pressure may be applied to the outer ends thereof. The two parts of the die can thus be brought into contact with one another and with the sleeve before applying pressure to the keys, whereby the sleeve is wholly surrounded and the metal of the sleeve is prevented from flowing outwardly between the two die parts, as has been the case heretofore.

If desired, instead of each die-part being provided with a single key which necessitates a succession of pressing operations, it may be provided with the number necessary for contracting the sleeve around the whole of its inner circumference and means may be provided for applying pressure simultaneously to all the keys.

Instead of providing a key in each die-part with a wavy edge as described with reference to Figures 3 and 4, each key may be provided with a back plate 29 (see Figures 6 and 7) from which extend a number of pins 30. The pins are arranged to extend through holes in the two die parts and are so spaced that the pins in one

die part are disposed opposite the gaps between the pins in the other die part. The back plates are urged outwardly from their respective die parts by compression springs 31 located in depressions 32 in the back plates and die parts. The tips of each pin as viewed in the direction of Figure 6 are convexly shaped and as viewed in Figure 7 are concavely curved to suit the curvature of the sleeve being operated upon. Such an arrangement is particularly suitable for contracting a steel sleeve on to a steel core.

In any of the constructions referred to above, the two die parts may be guided into correct registration with one another by the provision of interengaging dowels and dowel sockets.

I claim:

A method of attaching sleeves having eye portions to the core and sheath of a steel cored aluminium sheath cable in which both the core and the sheath are stranded comprising attaching a steel sleeve having an eye portion extending from one end thereof, to an exposed portion of the stranded steel core, positioning an aluminium sleeve having an eye portion extending from one end thereof and offset with respect to the eye portion of the steel sleeve over the attached steel sleeve and over the adjacent portion of the stranded aluminium sheath, with the eye portion of the aluminium sleeve in register with the eye portion of the steel sleeve, wholly surrounding the portion of the aluminium sleeve positioned over the aluminium sheath to confine said portion of the sleeve against radially outward distortion, subjecting the portion of the

aluminium sleeve positioned over the aluminium sheath while so surrounded and in a single operation to inwardly directed radial pressure over a part of the external surface thereof extending longitudinally of the aluminium sleeve, to secure the aluminium sleeve to the aluminium sheath, said pressure being limited to that just sufficient to press inwardly from the inner surface of the aluminium sleeve an amount of metal that will fill the gaps between strands of the aluminium sheath opposite the inwardly pressed part so that the length of the aluminium sleeve will remain substantially constant and the eye portions of the steel and aluminium sleeves will remain in register.
